ATTORNEY

UNITED STATES PATENT OFFICE.

FRANK J. DUNLEAVY, OF SAN FRANCISCO, CALIFORNIA.

BUCKLE.

1,269,066.

Specification of Letters Patent. Patented June 11, 1918.

Application filed May 24, 1916. Serial No. 99,606.

To all whom it may concern:

Be it known that I, FRANK J. DUNLEAVY, a citizen of the United States, residing at San Francisco, in the county of San Francisco and State of California, have invented certain new and useful Improvements in Buckles, of which the following is a specification.

My invention relates to a buckle and its 10 main object is to provide a novel and efficient form of connecting article of this nature which may be manufactured at exceptionally low cost and be adapted for manufacture in one piece.

15 More specifically, I aim to provide a buckle with parts rigidly connected together and consisting of a central straddle bridge with clamping members on each of opposite sides thereof, respectively connected there- 20 to at opposite ends of the buckle and at the other ends being cut away to enable insertion of the article to be buckled and having lugs to overlap the article at the cut away portions and prevent displacing movement 25 of the article.

Other objects and advantages will be pointed out as the following description progresses, and which is to be taken in connection with accompanying drawings illustrating one preferred embodiment.

In said drawings:—

Figure 1 is a fragmentary view in side elevation, illustrating my improved buckle in connection with a belt;

25 Fig. 2 is a bottom or inverted plan view of the parts of Fig. 1;

Fig. 3 is a cross sectional view on the line 3—3 of Fig. 1, and

40 Fig. 4 is a detail view of a modified form of clamping arm.

Referring specifically to the drawings, wherein like reference characters designate like or similar parts, the improved buckle is shown at A as connecting end portions 5 45 and 6 of a belt B together. While I have shown and will describe the invention in connection with a belt, it is not to be understood that a limitation to use in connection with a belt is to be imported, since the article is capable of use as a buckle generally and additionally for instance in connection with straps, saddlery, and regardless of the

specific material from which same is constructed.

Preferably the buckle is made of a single 55 piece of metal so as to have a central straddle bridge 7, a binder or clamp arm 8 extending parallel thereto but spaced therefrom and connected thereto at one end by means of a connector section 9. Connected 60 with the opposite end of the bridge 9 is a connecting section 10 for a clamp or binder arm 11 similar to the arm 8 and being parallel thereto and to the bridge 7.

The end portion 5 of the belt is in the form 65 of a loop as seen in Figs. 2 and 5 anchored or fastened to the bridge 7. The free end of the belt is insertible into the spaces intermediate the arms 8 and 11 and the straddle bridge, adapted to seat on the portion 5 and 70 be engageable with the inner edges 12 and 13 of the arms 8 and 11 respectively. The free ends of the arms 8 and 11 terminate in lugs 14 and 15, respectively, opposite the portions 10 and 9 and spaced therefrom to provide insert openings 16 and 17.

When the belt is unbuckled, the end 5 is merely connected to the straddle bridge and end 6 is free. In order to attach the end 6 or buckle it, it is passed through the openings 16 and 17 while at an angle to the other section so as to enter the spaces intermediate the arms 8 and 11 and the straddle bridge bind with the portion 5 and with the edges 12 and 13 so that tension of the belt will 85 maintain the portion 6 buckled to the portion 5. Straddle bridge 7 is so arranged that when the portion 6 is buckled, it will not be straight, so that the binding action with the edges 12 and 13 will be increased. 90 To unbuckle the portion 6 it is merely necessary to relieve the belt of tension and then turn the portion 6 at an angle to the portion 5 so that it may detach by movement through the openings 16 and 17. It will be realized that the lugs 14 and 15 overlap the portions 6 adjacent the openings 16 and 17 so as to prevent displacement or detachment of the portion 6.

In some instances, it will be desired to 100 serrate the edges 12 and 13 to increase the binding action on the belt. Such a serrated edge is shown at 18 on the binder arm 8 in Fig. 4. Since merely one embodiment of the in-

vention has been illustrated and described to set forth its principle, it is to be understood that changes in the details of construction may be resorted to within the spirit and scope of the invention.

I claim:—

A buckle including a straddle bar, clamping arms disposed on opposite sides of said bar and connected to the opposite ends thereof, said clamping arms having their adjacent longitudinal margins beveled to provide

downwardly and forwardly directed cutting edges, said cutting edges being disposed substantially in alinement with the upper edge of said straddle bar and serrated to provide penetrating teeth. 15

In testimony whereof I affix my signature in presence of two witnesses.

FRANK J. DUNLEAVY.
